[57] CLAIM

The ornamental design for a combined position-indicator switch face plate and key handle, as shown and described.

DESCRIPTION

FIG. 1 is a reduced perspective view of a combined position-indicator switch plate and key handle showing my new design, the cylindrical body of the switch shown in broken lines is for illustrative purposes only; FIG. 2 is an exploded side elevational view, the cylindrical body of the switch and the notched blade portion of the key shown in broken lines are for illustrative purposes only;

FIG. 3 is a front elevational view of the switch face plate shown separately for ease of illustration;

FIG. 4 is a front elevational view of the switch face plate and the key handle in assembled condition.

FIG.1.

FIG.2.

FIG.3.

FIG.4.
